(57) **CLAIM**

The ornamental design for a motorcycle drive shaft cover, as shown and described.

DESCRIPTION

FIG. 1 is a top perspective view of a first embodiment of a motorcycle drive shaft cover of the present invention.

FIG. 2 is a top plan view of the motorcycle drive shaft cover of FIG. 1.

FIG. 3 is a bottom plan view of the motorcycle drive shaft cover of FIG. 1.

FIG. 4 is an elevational view of a first end of the motorcycle drive shaft cover of FIG. 1.

FIG. 5 is an elevational view of a second end of the motorcycle drive shaft cover of FIG. 1.

FIG. 6 is an elevational view of a first side of the motorcycle drive shaft cover of FIG. 1.

FIG. 7 is an elevational view of a second side of the motorcycle drive shaft cover of FIG. 1.

FIG. 8 is a top perspective view of a second embodiment of a motorcycle drive shaft cover of the present invention.

FIG. 9 is a top plan view of the motorcycle drive shaft cover of FIG. 8.

FIG. 10 is a bottom plan view of the motorcycle drive shaft cover of FIG. 8.

FIG. 11 is an elevational view of a first end of the motorcycle drive shaft cover of FIG. 8.

FIG. 12 is an elevational view of a second end of the motorcycle drive shaft cover of FIG. 8.

FIG. 13 is an elevational view of a first side of the motorcycle drive shaft cover of FIG. 8; and,

FIG. 14 is an elevational view of a second side of the motorcycle drive shaft cover of FIG. 8.

Those portions of the cover shown in broken lines are included for illustrative purposes only and form no part of the claimed design.
